UNITED STATES PATENT OFFICE

PERCY H. THOMAS, OF UPPER MONTCLAIR, NEW JERSEY

UNIVERSAL TRANSMISSION TOWER

Substituted for application Serial No. 158,314, filed December 31, 1926. This application filed February 6, 1929. Serial No. 238,006.

The present case is an improvement on my Patent No. 1,616,932, entitled Improvements in universal transmission tower, dated February 8th, 1927.

My invention relates to supporting towers for electric transmission lines and particularly to towers of steel or other material of great rigidity and strength and offers a particularly rugged and economical structure.

I show a tower composed of elements which can be assembled in more than one relation to accommodate the construction to various conditions at the point of installation as will appear hereinafter.

This tower makes use of a number of design principles shown in my Patent No. 1,616,931, entitled Transmission line towers for electric circuits, dated February 8th, 1927, and my application Serial No. 67,159, filed November 5th, 1925, Transmission line towers.

I have shown in Figs. 1, 2 and 3 a form of tower with four posts and transverse guys, located on level ground. Fig. 1 is an elevation taken looking along the line and toward the left in Fig. 3. The lacing in the posts 5^a, 5^b, is not shown for clearness. Fig. 2 is an end elevation taken looking toward the top of the sheet in Fig. 3, certain crossarm members not being shown. Fig. 3 is a plan view of the left hand end of the tower as shown in Fig. 1.

Figs. 4, 5 and 11 show certain details, especially a method for flexibly connecting a pair of posts to one end of the crossarm. Fig. 4 is an elevation of an extension 9 of the crossarm taken looking toward the top of the sheet in Fig. 3, and Fig. 5 is a plan of the same. Certain elements are shown partly or wholly by center lines and certain are not shown at all for purposes of clearness. Fig. 11 is a perspective view of the construction shown in Figs. 4 and 5, certain crossarm members being broken away for the purpose of clearness. This view is taken looking out from

the paper and from the left toward the right in Fig. 2 and from the upper left hand corner of the sheet toward the end of the crossarm that is not shown in Fig. 3. In Figs. 4, 5 and 11 certain members at the end of the crossarm supporting the conductor 2 are not shown.

In Fig. 6 the same tower is shown located on ground sloping across the line making an inclination of 25% with the horizontal, this view being an elevation taken the same as Fig. 1. Fig. 7 is an elevation of the same tower taken looking across the line located on ground sloping both along and across the line. Figs. 8 and 9 are respectively an end view and a partial plan respectively of another form of tower made up of the same elements as the tower of Fig. 1 and having two posts only, but having both transverse and longitudinal guys. Certain parts are omitted for clearness.

Fig. 10 shows an elongated post for applicant's tower, having an extension inserted at the middle.

In Figs. 1, 2, 3, 4 and 5, showing a four post form of tower, 1 is a crossarm supporting six electrical conductors, 2, 2, and two ground wires 3, 3. Insulator strings supporting the conductors are shown at 4, 4. The crossarm 1 is framed preferably of steel members such as structural angles put together in the usual way. The crossarm may be supported by two pairs of posts 5^a, 5^b and 5^a, 5^b attached to the crossarm 1 at their upper ends, but spread apart lengthwise of the line at the lower ends. The posts may be supported on any suitable foundations 6, 6 at the ground level, tripods being shown in the illustrations. These posts are so designed and connected to the crossarm that no material bending moment will be introduced in the posts by any movements of the crossarm within reasonable limits. The crossarm will normally be held firmly in place against all stresses acting on it, but should a foundation settle, or a connection

stretch a little or the guys be tightened unevenly, there would be a certain movement of the crossarm but this would throw no bending stresses into the posts. This is important since bending stresses would be very severe on the posts.

Similarly the posts are so connected to the foundations or the foundations are so designed that any angular movement of the posts corresponding to the limited movement of the crossarm already described will not throw bending stresses into the post. The post may be hinged to the foundations as shown for longitudinal motion in Figs. 1 and 2 where the post is carried on a bolt 35, which in turn passes through the tops of the three angles 36 connected in the form of a tripod, with a base 37, or the connection may merely be designed for flexibility as for example, as shown for transverse motion in Figs. 1 and 2 also.

The crossarm is restrained from lateral motion by the transverse guys 7 and 8. Each of these guys is connected to an extension 9 fastened to the crossarm 1 and divides at the connector or equalizer 7^c and 8^c into two guy rods, 7^a, 7^b and 8^a, 8^b respectively. These divided guy rods are connected to anchors or foundations near the bottom of the posts 5^a and 5^b as shown. By this arrangement I secure the distribution of the stresses produced in the posts by the transverse pull on the crossarm and when the guys are connected directly to the foundations of the posts, as here shown, the weight of the tower and its load at each post is in opposition to any uplift on the guy. I further secure an attachment of the transverse guys 7 and 8 to the crossarm 1 in such a way that no bending in a plane perpendicular to the crossarm is produced and no bending stresses in the posts. This arrangement further serves to give an indication of the relative tightness of either pair of guys 7^a, 7^b or 8^a, 8^b for the connectors 7^c and 8^c will be pulled to one side if either guy of the pair is too tight. The guys 7 and 8 are attached to the extensions at a point on the central plane of the crossarm.

Longitudinal stresses on the crossarm whether due to conductors, ground wires, wind or other cause are taken up by horizontal components of the axial stresses in the posts, for these posts taking no bending have only axial stresses. The vertical components of the stresses in the posts due to horizontal longitudinal stresses on the crossarm are equal and of opposite sign and neutralize each other at the top.

All downward stresses including the weight of the crossarm are divided between the four posts according to the well known laws of mechanics.

I have not shown the details of the particular framing of the crossarm or the posts and foundations for this will be evident to those

skilled in the art. Certain members are omitted for the sake of clearness, as for example, the bracing of the posts 5^a and certain details of the extension 9. I have shown the arrangement of elements, however, and all the features necessary for the understanding and utilization of the novel features of my tower.

In Figs. 4 and 5 which are respectively an elevation and a plan, I have shown enlarged the extensions 9, 9 of the crossarm 1, to which are attached the posts 5^a, 5^b, 5^a, 5^b and details of suitable connections between the posts and the crossarm. In these figures I have used center lines or gauge lines largely to represent the steel members which will usually be of structural steel angles. I have shown portions of angles in outline where this is necessary for clearness. Fig. 11 shows in perspective the same construction as Figs. 4 and 5, the same numerals being applied to the same members in all the figures. The crossarm is shown as extending backwardly and to the right. The angles 33, the plates 30, 30, 22, 23, 24 and bolts 25, 26 and 27, forming the flexible connections between the posts and the crossarm are shown clearly. The members 19, 20 are braces bolted to the flanges of the angles 12, 13 and 17, 18.

Referring to Fig. 4, 10 is a strut or tie angle, being a part of the crossarm shown also in Fig. 3 and in Fig. 7. This is the member to which a ground wire may be connected when used. This member 10 connects the two main crossarm chord angles 28, 28.

The post 5^a is connected to the extension 9 by two heavy bolts 25 and 26 acting as hinges between the crossarm and the post for motion of the crossarm transversely. In the post these bolts are carried by two pairs of plates 30, 30, bolted or riveted to the main angles 31, 31, of the post 5^a, two angles being connected to one pair of plates. These bolts 25 and 26 pass through holes in the plates 22 and 23 which are part of the crossarm extension 9 this securing the posts to the crossarm in such a manner as to permit free motion of the crossarm transversely without putting bending moment in the posts. This connection, however, is stiff against angular motion in the plane containing the axis of the post and the two bolts 25 and 26. This stiffness is useful in steadyng the crossarm against wind pressure along the line, which would otherwise overturn the crossarm. However, this wind pressure is only that acting on the members above the plane of the angles 28, for stress in that plane is resisted by the posts by axial stresses, these posts having their axis meeting in the line of the centers of the members 10, see Fig. 4. The residual bending moment of longitudinal wind must be taken by the posts but will be so small as to be unobjectionable. The post is given a suitable cross sectional shape for this purpose.

130

The plates 22 and 23 taking the stresses from the post 5^a are carried by two angles 12 and 13 connecting to the plate 21 secured to the member 10 at its center and the angles 16 and 17 connected at the point 29^a (see Fig. 5) to the angles 39, 39, which are extensions of the angles 28, 28 and also to the angle 32 (see Fig. 1) from above. The plates 22 and 23 are connected together by the angle 19, secured to the legs of the angles 12 and 13.

The post 5^b is connected to the crossarm extension 9 through the plate 24 by means of the bolt 27, much in the same way as post 5^a, but a single bolt is used so that the connection 15 may be flexible both transversely and longitudinally. The plate 24 and the bolt 27 are secured to the post at the center point of its top by two angles 33, which run across the post to transfer the stresses to the plates 30, 30 and 20 the main corner angles 31. The plate 24 is carried by the angles 14 and 18 connected respectively to the plate 21 and to the angles 16 and 17 and 32 at the point 29^a. The plates 23 and 24 are connected together through the angle 20. It will be noticed that a transverse movement of the crossarm 1 will tend to bend the plates 22, 23 and 24, since they do not lie strictly in parallel planes. However, in practice this will be of no disadvantage because 30 for any degree of motion likely to exist the amount of this bending will not be important and because the posts are free to rotate on their axes to a certain extent.

The angles 11 and 15 connect the plates 22 and 24 to the angles 28 at their point of connection to the ends of the member 10, securing the crossarm against overturning.

There is advantage in using a connector or equalizer 34 at the point where the guys 7^a, 8^a and 7^b, 8^b, cross as this supports these guys and gives a certain control of the clearance between the conductors 2 and the guys by determining the angle at which the guy 7 or 8 leaves the post top.

Turnbuckles or other length adjustment means 40 should be inserted in the guys at a sufficient number of points to permit adjustment of stress and position for all guys.

Certain members have been omitted in these figures to clarify the drawings so that the construction may be clear, but they may easily be supplied by those skilled in the art.

This tower of Figs. 1, 2 and 3 may be used on sloping ground. If the slope is across the line, the posts may still be placed vertical and the guys readjusted as shown in Fig. 6. In this case the crossarm will be generally parallel to the surface of the ground. The clearance from the conductors to the guys will be somewhat affected but not seriously and in any case any desired clearance may be provided for by design. This use of my tower avoids the necessity of excavation of the ground on the high side or building up under 60 the posts on the lower side on such sloping

ground. This is often of very great advantage.

When the ground slopes with the line the tower may be installed on the actual surface of the ground as it lies throwing the center line of the tower off the vertical and for reasonable slopes no material disadvantage results. The stresses due to dead load are increased on the downhill posts but the stresses due to longitudinal load are decreased on this post, so that for reasonable angles no special construction is required. This condition is shown in Figure 7 in which the tower of Fig. 2 is shown on ground sloping both with and across the line, the ground under the back posts being the higher. In Figs. 6 and 7 the same posts are designated by the same numerals as in Figs. 1, 2 and 3. In Fig. 7 some members have been omitted for the sake of clearness, but they may be readily supplied by those skilled in the art.

By this method of adjusting the tower to the slope of the ground I avoid much expense and difficulty in side hill extensions such as are required in many towers of the standard type.

In general I prefer to fabricate the posts in two parts, such part being assembled and galvanized in the shop and the two being bolted together in the field, the separation being at or near the middle of the section being square at this point. In this case all four posts may be made of identically the same members, the top halves being assembled on the lower halves with the post 5^a in a position at right angles to that for posts 5^a. The plates 30, 30 may be used in all post tops but the angles 33 must be added in post 5^b to carry the bolt 27.

Where circumstances permit I may use two posts, for example, two posts 5^a of Figs. 1, 2 and 3 in place of 4. In this case I add longitudinal guys 38, Fig. 8, connected to each post preferably at the middle point of the member 10 of the crossarm corresponding to the member 10 of the Figs. 1, 2 and 3, these guys taking up longitudinal stresses. In this case the crossarm extension 9^a corresponding to the extension 9 of Figs. 1, 2, 3 must be somewhat differently framed since there is but one post 110 to be connected. Such framing need not here be shown as it involves no novel problems. The extension 9^a is symmetrical about a vertical plane through the middle of the cross-arm.

This tower of Fig. 8 is shown in plan in Fig. 9, where similar parts are similarly numbered. One of the transverse guys for the structure of Figs. 8 and 9 is shown at 7^a, the other guy 8^a being similar but oppositely placed. The longitudinal guys 38 may to advantage make a small angle with the center line of the transmission line to give a little support to the transverse guys and to improve the clearance from the conductors.

As shown in the various figures, on account of the transverse flexibility of the connections between post 5^a and the crossarm, and where four posts are used the flexibility in both directions of the connection between the post 5^b and the crossarm, the structure as a whole may be subjected to sinking of foundations, irregularities of installation, stretching or improper adjustment of guys, etc., without throwing undue stresses into the posts or other members of the tower. This is in contrast to the conditions in the standard four legged type of tower, wherein any yielding of foundations must cause serious strains in the rigid structure.

The present type of tower gives what might be called a universal structure which may be used for many sorts of sites and conditions as may be most convenient. Where ground space is important the arrangement of Figs. 1, 2 and 3 is suitable, while that of Figs. 8 and 9 is usually more economical where guys may be permitted. The arrangement of Figs. 8 and 9 is similar in many respects to structures shown in my applications Serial No. 67,159 and Patent 1,616,931 above referred to.

It will be noted that certain elements, the more important parts, are the same in all uses of the tower, while certain other parts, largely the connections, vary for different ground conditions and other causes. For example, both the upper and lower post sections are all the same, also the crossarm is always the same, excepting the extension 9 or 9^a which in this sense is to be taken as attached to the crossarm rather than a part of it.

The material and form of the guy also remains the same although the length varies. The connections, as for example the bolt hinges, are differently arranged for different embodiments also the guy connections and the guy lengths. This layout is favorable for economy for the special parts for the line as a whole are reduced to a minimum. Where the slopes of the ground are not uniform or where desirable for other reasons, I contemplate the lengthening of one or more posts to conform to the ground or other conditions. This lengthening is accomplished preferably by inserting a length of post between the top and bottom elements above described. Such an extension piece is shown in Fig. 10, where the member 41 is inserted between the post top 42 and the post bottom 43 of the post 5^a.

I claim as my invention:

1. A transmission line tower comprising a transverse crossarm carrying attachment points for conductor supports thereon, located in a plane of attachment, a foot on each side of the center under said crossarm and rigidly framed thereto, a single post under each of said feet taking downward axial loads and hinged to said foot to permit motion

across the line while resisting overturning of said crossarm, means for restraining motion across the line consisting of crossed ties connected to the points of connection between said feet and said posts and means for restraining longitudinal motion of said crossarm, said means being attached to said crossarm in the plane of said cable supports.

2. A transmission line tower comprising a transverse crossarm carrying attachment points for conductor supports thereon, located in a plane of attachment, a foot on each side of the center under said crossarm and rigidly framed thereto, a single post under each of said feet taking downward axial loads and hinged to said foot to permit motion across the line while resisting overturning of said crossarm, means for restraining motion across the line consisting of crossed ties attached at one end to the connection between the posts and the feet and at the other near the base of the opposite post and means for restraining longitudinal motion of said crossarm, said means being attached to said crossarm in said attachment plane.

3. A transmission line tower comprising a transverse crossarm carrying attachment points for conductor supports thereon, located in a plane of attachment, a foot on each side of the center under said crossarm and rigidly framed thereto, a single post under each of said feet taking downward axial loads and hinged to said foot to permit motion across the line while resisting overturning of said crossarm, means for restraining motion across the line consisting of crossed ties connected to the points of connection between said feet and said posts and means for restraining longitudinal motion of said crossarm, said means being attached to said crossarm.

4. A transmission line tower comprising a transverse crossarm carrying attachment points for conductor supports thereon, located in a plane of attachment, a foot on each side of the center under said crossarm and rigidly framed thereto, a single post under each of said feet taking downward axial loads and hinged to said foot to permit motion across the line while resisting overturning of said crossarm, means for restraining motion across the line consisting of crossed ties connected to the points of connection between said feet and said posts and means for restraining longitudinal motion of said crossarm, said means consisting of guys in pairs connected to said crossarm in the plane of said cable supports.

5. A conductor carrying crossarm having a horizontal truss for resisting longitudinal stresses, feet under said crossarm framed rigidly thereto on opposite sides of the center, a single post bearing axial stresses under each of said feet, hinged joints between said posts and said feet permitting freedom of

70

motion only across the line, foundations under said posts, and means for restraining motion across the line consisting of crossed tension members secured at the top to the 5 connecting points between said posts and said feet and at the bottom to said foundations.

6. A transmission line tower comprising a transverse overhanging crossarm, a single post supporting said crossarm on each side of 10 the center and foundations under said posts, said posts being each provided at the top with two separated hinge joint bearings operating in one plane and at the bottom with a single hinge joint bearing operating in a plane at 15 right angles to said first named plane.

7. A post in an articulated transmission line structure comprising a long column designed to take axial stresses, two hinged bearings at the top spaced apart in a direction 20 along the line and a single hinged bearing at the bottom set at right angles to said first named bearings.

8. A post in an articulated transmission line structure comprising a long column designed to take axial stresses, two hinged bearings at the top spaced apart in a direction 25 along the line and a single hinged bearing at the bottom set at right angles to said first named bearings, said post consisting of three 30 members, an upper member and a lower member both having tapered main legs and a central member having parallel main legs connected to said members with tapered legs.

9. A transmission line tower comprising a 35 transverse crossarm, carrying attachment points for conductor supports thereon located in a plane of attachment, two compression members under said crossarm one on each side of the center, hinges on said crossarm 40 to permit motion of the crossarm across the line, while resisting overturning of said crossarm, said hinges being located below said plane of attachment and means for restraining displacement of said crossarm 45 longitudinally and transversely, the forces resisting transverse displacement being applied near said hinges.

10. A transmission line tower comprising a transverse crossarm, carrying attachment 50 points for conductor supports thereon located in a plane of attachment, two compression members under said crossarm one on each side of the center, hinges on said crossarm to permit motion of the crossarm across the line, 55 while resisting overturning of said crossarm, said hinges being located below said plane of attachment and means for restraining displacement of said crossarm longitudinally, said means being attached to said crossarm 60 in said plane of attachment, together with crossed ties restraining transverse displacement of said crossarm connected near the opposite ends of said compression members.

11. A transmission line tower comprising 65 a transverse overhanging crossarm, a single

post supporting said crossarm on each side of the center and foundations under said posts, said posts being each provided at the top with two separated hinge joint bearings operating on the same axis and at the bottom with a single hinge joint bearing operating 70 in a plane at right angles to said axis.

Signed at New York, in the county of New York and State of New York this 5th day of February, A. D., 1929.
